UNITED STATES PATENT OFFICE.

MONTE C. LOOMIS, OF MANKATO, MINNESOTA.

SMALL-ARM EXPLOSIVE SHELL.

Application filed September 20, 1926. Serial No. 136,560.

This invention aims to provide a novel form of bullet, adapted to be used, ordinarily, in small arms, and so constructed that when it strikes an obstacle, it will explode. 5 It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the drawings:—

20 Figure 1 shows in elevation, a device constructed in accordance with the invention; Figure 2 is a longitudinal section; Figure 3 is a cross section on the line 3—3 of Figure 2;

25 Figure 4 is a cross section on the line 4—4 of Figure 2.

The device forming the subject matter of this application comprises a casing 1 of tubular form, and made of steel. Within 30 the casing 1 is located the body 2 which is made of softer metal than the casing 1, the constituent metal of the body 2 being soft enough so that it will mushroom when the bluntly pointed end 3 of the body strikes 35 an obstacle. The body 2 is secured in the casing 1 and is supplied in its rear end with a chamber 4 for the explosive, this chamber, preferably, but not necessarily, being of conical outline. In the body 2 is embedded a 40 firing pin 5, made of hard metal, the rear end of the firing pin 5 projecting into the chamber 4 and carrying an enlarged head 6, which may be in the form of a ball, the head 6 being alined with a projection 7 on a butt

piece 8 which is threaded at 9 into the rear 45 end of the casing 1, the butt piece 8 having a polygonal projection 10 whereby the butt piece may be rotated to thread it into the casing 1. The chamber 4 contains the explosive 11 which is located about the head 50 6 of the firing pin 5 and about the projection 7 on the butt piece 8.

In practical operation, when the nose of the body 2 strikes an obstacle, the nose mushrooms, the firing pin 5 is driven backward, and the head 6 of the firing pin strikes the projection 7, the said projection being in the form of a cap which will set off the explosive 11 in the chamber 4, the bullet then bursting with great effect. 60

The bullet hereinbefore described is assembled with a cartridge (not shown) containing a propelling charge.

What is claimed is:—

A bullet including a tubular casing, a 65 butt piece threaded into the rear end of the casing, the butt piece being provided with means whereby it may be rotated, the butt piece being provided on its inner surface with a projection, a body within the casing 70 and in engagement with the butt piece, the body having a chamber in its rear end, for the reception of an explosive, to hold the explosive about the projection, and a firing pin mounted in the body and extended 75 backwardly into the chamber, the firing pin being provided with an enlarged head located in the chamber and in alinement with the projection on the butt piece, the constituent material of the body being soft enough 80 so that it will mushroom and drive the firing pin backwardly, thereby carrying the head of the firing pin into engagement with the projection on the butt piece.

In testimony that I claim the foregoing 85 as my own, I have hereto affixed my signature.

MONTE C. LOOMIS,
